[57] CLAIM

The ornamental design for a collapsible fishing rod, as shown.

DESCRIPTION

FIG. 1 is a top rear perspective view of a collapsible fishing rod showing my new design in collapsed condition and with an attached reel being shown in broken lines for illustrative purposes only.

FIG. 2 is a top front perspective view thereof in its extended position;

FIG. 3 is a top plan view thereof;

FIG. 4 is a side elevational view thereof;

FIG. 5 is a rear elevational view thereof;

FIG. 6 is a front elevational view thereof;

FIG. 7 is a side elevational view thereof opposite to that shown in FIG. 4; and

FIG. 8 is a bottom plan view thereof.
